(57) **CLAIM**

The ornamental design for a catheter package, as shown and described.

DESCRIPTION

FIG. 1 is a perspective view of catheter package showing my new design;

FIG. 2 is a front elevation view of the catheter package illustrated in FIG. 1;

FIG. 3 is a back elevation view of the catheter package illustrated in FIG. 1;

FIG. 4 is a left side elevation view of the catheter package illustrated in FIG. 1;

FIG. 5 is a right side elevation view of the catheter package illustrated in FIG. 1;

FIG. 6 is a top plan view of the catheter package illustrated in FIG. 1; and,

FIG. 7 is a bottom plan view of the catheter package illustrated in FIG. 1.

In FIGS. 1-2 and 4-7 a packaging label with instructions printed on the label is illustrated in broken lines that form no part of the claimed design.

In FIGS. 1-2 and 6-7 a vertical seal on a front of the package is illustrated in broken lines that form no part of the claimed design.

In FIGS. 3 and 6 a die cut pattern formed in a tab of the catheter package is illustrated in broken lines that form no part of the claimed design.

1 Claim, 7 Drawing Sheets
